CROSS-OVER NETWORK HOUSING FOR TELEVISION ANTENNAS

Edwin E. Ritter, Chalfonte, Pa., assignor to Hugh H. Eby, Inc., Philadelphia, Pa., a corporation of Pennsylvania

Application January 12, 1954, Serial No. 28,482

Term of patent 14 years

(Cl. D26—14)

To all whom it may concern:

Be it known that I, Edwin E. Ritter, a citizen of the United States, and a resident of Chalfonte, county of Bucks, State of Pennsylvania, have invented a new, original, and ornamental Design for a Cross-Over Network Housing for Television Antennas, of which the following is a specification, reference being had to the accompanying drawings forming a part thereof, wherein:

Figure 1 is a rear perspective view of the cross-over network housing for television antennas showing my new design;

Figure 2 is a front perspective view thereof;

Figures 3 and 4 are, respectively, top and bottom plan views thereof; and

Figures 5 and 6 are, respectively, rear and end elevational views thereof.

I claim:

The ornamental design for a cross-over network housing for television antennas, substantially as shown.
